PINKING INSTRUMENT

José Antonio Salas, Caracas, Venezuela, assignor
to American Samec Corp., New York, N. Y., a
corporation of New York

Application January 6, 1949, Serial No. 69,513
In Venezuela September 23, 1948

7 Claims. (Cl. 30—178)

1

The present invention relates to a device for cutting sheet material by means of a toothed wheel, such as a pinking instrument. The particular feature of this invention resides in the fact that the toothed wheel is urged against a smooth roller or anvil in a resilient manner and not in a rigid manner as has been the case heretofore. In other devices or instruments of this type, there is but a metal spring employed for supporting the toothed wheel and the smooth wheel or roller that contacts the wheel. This requires strong pressure in obtaining continuous contact between the two wheels for compensating for the lack of perfect circumferential engagement of the wheels, the same being practically impossible to obtain in the mass production of the devices of this class which sell for a relatively cheap price.

An object of this invention is to provide a shears of the pinking type wherein the main body consists generally of three separate parts.

Another object of the invention herein is to construct a pinking shears for cutting any sheet material, such as leather, cloth, sheet metal, etc., with a minimum of effort.

A still further object of the invention herein is the provision of clamping means for securing the two separate parts of the main body together and thereby to dispose said wheels in circumferential relation to one another.

An even further object of this invention is the provision of a resilient strip disposed between the attached parts of the main body so as to lend flexibility to the idler wheel.

Yet a further object is to construct a pinking shears wherein the smooth or idler roller and the pinking or cutter wheel are adapted to be adjusted as regards the circumferential pressure therebetween.

An even yet further object of the invention is to construct a pinking shears wherein the gear adjacent the cutter rotates on a ball bearing.

These and other objects and advantages will be in part obvious from the annexed drawing and in part hereinafter indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the modifications in structure and relation contemplated by this

invention, a drawing depicting certain forms of the invention has been annexed as a part of this disclosure, and in such drawing, like characters of reference denote corresponding parts throughout all the views, of which:

Fig. 1 is a side elevation of a pinking shears according to this invention;

Fig. 2 is a bottom view of the device shown in Fig. 1;

Fig. 3 is a bottom view, partly in section, showing the larger cutter-carrying body part and the tension spring in the pinion in section; the smaller or idler-carrying body part being removed for clarity;

Fig. 4 is an end view of the top portion of the device, showing the resilient strip; and

Fig. 5 is a fragmentary sectional view of a ball bearing for the anvil wheel, representing another modification of this invention.

The pinking shears comprising this invention consists of a main body 10 which is the cutter-carrying member to which is secured the roller-carrying member 11 by means of a screw 12. Screw 12 is inserted in member 11 by way of the bore 13 therein and is screwed into the main body

10. Main body 10 has a hollow portion 10a which is open at its end 10b and a side 10c, its opposite side having a longitudinal slot 10d. Pivottally attached to body 10 by means of a set screw 14 is a lever arm 15 which has teeth 16 at one end thereof in engagement with teeth 17' of hollow pinion 17. Lever arm 15 extends through slot 10d. Pinion 17 is rotatably mounted on a hollow shaft 17a extending from cutter 18. Pinion 17 has an annular recess 41 within which fits a coiled torsion spring 20 having one end caught in the space between two adjacent teeth of pinion 17. Spring 20 acts as a one-way clutch to grip the shaft 17a when the pinion 17 is rotated in one direction by action of lever 15, and thus cause rotation in one direction of cutter 18. Nut 40 fixed to shaft 17a on the other side of cutter wheel 18 acts as a spacer and abutment. A set screw or shaft 19 passes through the hollow of shaft 17a and supports the foregoing assembly

45 on body 10 substantially at the juncture of open end 10b and open side 10c. The toothed portion of lever arm 15 is disposed within the hollow portion 10a of body 10. Body portion 11 has an extension 21 provided with two projecting arms 22 between which is rotatively supported anvil or idler wheel 23 having the extended portion 24 and being mounted on shaft or set screw 25 supported on extension 21. Numeral 26 represents

50 the resilient strip which is secured between shoul-

der extensions 27 and 28 of bodies 10 and 11 respectively; the said strip 26 acting as a cushion in absorbing the downward pressure of lever arm 15 and thereby rendering flexibility to idler 23. Bore 13 of body portion 11 conforms into a spherical seat 29 for the abutment of annular shoulder 30 on set-screw enlarged portion 12'. A clearance 13' is formed between the wall of bore 13 and screw portion 12' so that when cutting pressure is exerted, screw 12 will be better adapted to render said wheels 18 and 23 elastic as regards the cutting pressure therebetween. The circumferential pressure between the wheels 18 and 23 and the tension on the resilient strip 26 may be adjusted by merely inserting a screw-driver or the like, or even a coin, in slot 31 of screw head 32 and turning the screw accordingly till the proper adjustment is attained for the cutting of a certain material. Lever arm 15 is formed with an aperture 33 for the insertion of the operator's thumb while the main body 10 has a finger-hold 34 which is adapted to be gripped by the fingers of the hand of the said operator. Numeral 42 represents a lug extending from body portion 11 and abutting body 10 adjacent lug 27.

In the modification depicted in Fig. 5, there is seen a rubber or like seal 35 and a spring-lock washer 36 enclosing a ball bearing 37 in anvil or idler wheel 38; the said ball bearing 37 providing effortless rotation of said wheel 38 about shaft 39.

The operation of the pinking shears is as follows:

The device is first gripped by the operator's thumb which is inserted in aperture 33 and by the fingers which engage fingerhold 34. Following this, pressure exerted on the finger parts 33 and 34 by the operator will cause lever arm 15 to pivot at 14, relative to said body 10, to such an extent that teeth 16, at the end of lever arm 15 opposite aperture 33 thereof, will move in the direction of the arrow and impart a rotative movement to toothed or cutter wheel 18 by the intermeshing of said teeth 16 with teeth 17' of the associated gear 17 of said wheel 18. The idler wheel 23 acting as a rotatable anvil for the cutter wheel 18 will move in the direction of the arrow upon rotation of said cutter wheel 18; the said wheels thereby gripping, inwardly drawing, and then cutting the material (not shown in drawing) therebetween. Because of torsion spring 20, pinion and not cutter 18 will rotate in the opposite direction, when the lever arm is raised.

It is to be observed that the adjusting screw 12 is disposed intermediate the resilient strip 26 (which may be made of natural or synthetic rubber, or any other suitable resilient or elastomeric material) and the contacting wheels 18, 23. The diameter of bore 13 above seat 29 is slightly larger than the diameters of screw portion 12' and screw head 32 to give the necessary play for the resilient adjustment purposes as hereinbefore stated. Thus, both resilient strip 26 and adjusting screw 12 coact or cooperate to bring about the adjustment and resiliency of the cutting pressure between the contacting wheels 18, 23.

Having thus described my invention, what I claim as new and desire to secure by Letters Patent is:

1. A pinking instrument for cutting material, comprising three separate parts, one of said parts comprising a lever having a toothed end and two other of said parts each carrying a

wheel, one being a cutter and the other an anvil, said wheels having their respective circumferences in contacting engagement, a pin adjustably securing together said two other of said parts, said pin being disposed in a bore having a spherical seat formed in one of said two other of said parts, said pin having a shoulder abutting against said seat, said lever being pivotally secured to one of the two other of said parts carrying the cutter, means meshing with said toothed end of the lever for imparting rotation to said wheels by actuation of said lever for the cutting of said material, and resilient means disposed between said two other of said parts comprising cushioning means for said wheels and cooperating with said pin and said seat to impart a slight degree of flexibility to said two other of said parts.

2. A pinking shears according to claim 1 wherein said bore is of a diameter greater than that of said pin thereby providing a clearance for said shoulder for adjustment purposes and rendering said wheels relatively elastic to one another.

3. In a pinking instrument for cutting sheet material; the combination of two separate wheel supporting members disposed in side by side relationship, a wheel at one end of each of said supporting members in circumferential alignment with each other, one of said wheels constituting a cutter and the other of said wheels constituting an anvil, means engaging one of said supporting members intermediate its ends and rockably and adjustably mounting said one supporting member on the other of said supporting members, resilient means interposed between the other end of said one supporting member and said other supporting member so that the peripheries of said wheels effect resilient contact with each other, and means carried by one of said supporting members for effecting rotation of said wheels.

4. In a pinking instrument for cutting sheet material; the combination according to claim 3, wherein said means rockably and adjustably mounting said one supporting member on the other of said supporting members includes a screw member tapped into said other supporting member, and a bore in said one supporting member intermediate its ends loosely receiving said screw member to permit rocking of said one supporting member.

5. In a pinking instrument for cutting sheet material, the combination according to claim 4, wherein said bore is formed with a portion of reduced diameter having a spherical seat thereon, and said screw member is formed with a shoulder engageable with said spherical seat to hold said one supporting member on said other supporting member.

6. A pinking instrument for cutting material, comprising two separate parts, a wheel on each of said parts having their respective circumferences in contacting engagement, one of said wheels being an anvil and the other of said wheels being a cutter, a pin securing said separate parts together and adjustable longitudinally at right angles to the plane of separation between said parts, said pin being disposed in a bore of greater diameter having a spherical seat formed in one of said parts, said pin having a shoulder abutting against said seat, resilient means disposed between said parts constituting cushioning means for said wheels and cooperating with said pin and said seat to impart a slight

degree of flexibility to the connection of said parts, and means carried by one of said parts operatively connected to the wheel thereon for effecting rotation of said wheels.

7. A pinking instrument for cutting material, comprising two separate parts having inner edges thereof in confronting relationship, each of said parts carrying a wheel adjacent one end with the circumferences of said wheels contacting each other and the axes of rotation thereof being disposed in planes parallel to the plane of separation between said confronting inner edges, a bore formed in one of said parts at right angles to said plane of separation and having a spherical seat formed at the end of the bore adjacent to said inner edge of said one part, a screw member loosely extending in said bore and tapped into the other of said parts to be longitudinally adjustable, a shoulder on said screw member abutting against said seat for holding said one part to said other part, a resilient member interposed between the other end of said one part

and said other part to provide a cushioned contact between the circumferences of said wheels, one of said wheels constituting a cutter and the other of said wheels constituting an anvil, and means carried by one of said parts operatively connected to one of said wheels for effecting rotation of said wheels.
